C. K. VOLCKENING.
STEM FOR BOTTLE WASHING BRUSHES.
APPLICATION FILED DEC. 23, 1908.

922,982.

Patented May 25, 1909.

UNITED STATES PATENT OFFICE.

CHARLES K. VOLCKENING, OF NEW YORK, N. Y.

STEM FOR BOTTLE-WASHING BRUSHES.

No. 922,982.

Specification of Letters Patent.

Patented May 25, 1909.

Application filed December 23, 1908. Serial No. 468,895.

To all whom it may concern:

Be it known that I, CHARLES K. VOLCKENING, a citizen of the United States, and a resident of the city of New York, borough 5 of Brooklyn, in the county of Kings and State of New York, have invented a new and Improved Stem for Bottle-Washing Brushes, of which the following is a full, clear, and exact description.

10 My invention relates to stems used for bottle washing brushes, my more particular purpose being to provide a type of telescopic stem adapted to rotate at a high rate of speed and carrying a brush upon one of its 15 ends, the stem being not only compressible in the general direction of its length, but being so constructed that when an undue pressure is applied upon the end of the stem, the rotation of the stem, acting in conjunction 20 with the pressure, tends to shorten the stem to a greater extent than could be accomplished by the undue pressure alone.

More particularly stated, my invention comprehends a tubular stem comprising an 25 upper spindle and a lower spindle fitted telescopically together, the lower spindle being provided with a spiral slot, the walls of which serve as a cam, the upper spindle being provided with a lug fitting into said 30 slot, so that when both spindles are driven by power applied to the lower spindle and undue pressure is applied upon the upper spindle in the general direction of its length, the action of the lug within the cam which 35 it fits, assisted by the continuous rotation of the lower spindle, tends to draw the upper spindle downward so that the brush carried by the upper spindle is correspondingly lowered.

40 The purpose of my invention, generally speaking, is to facilitate the quick withdrawal of the bottle washer brush from contact with any obstruction which this brush meets in washing the bottle, the withdrawal 45 being controlled by the obstruction, but the motive power for effecting the withdrawal being supplied from the power used for turning the stem.

Reference is to be had to the accompanying 50 drawings forming a part of this specification, in which similar characters of reference indicate corresponding parts in all the figures.

Figure 1 is a view partly in section and

partly in elevation, showing a portion of a 55 bottle washing machine, and also showing how the improved stem is used in connection with said machine; Fig. 2 is a fragmentary elevation of the upper and lower tubular spindles showing the slot and the 60 lug fitting the same, these parts together constituting a portion of the means whereby, under proper conditions, rotation of the lower spindle lowers the upper spindle; and Fig. 3 is a central vertical section through 65 the mechanism indicated in Fig. 2, and shows in addition a stout spiral spring for tensioning the upper and lower tubular spindles relatively to each other.

Mounted upon a vertical rod 4 is a bracket 70 5 and engaging the same is a lug 6 carried by a collar 7 constituting a bearing. A collar 8 is slidably mounted upon the rod 4 and is provided with a lug 9. A holder 10 engages this lug and is integral with a plate 75 11, and resting upon this plate is another plate 12. A bar 13 is connected with the collar 8 and is provided with a handle 14. A collar 15 is mounted upon the rod 4 and journaled in this collar is a rocking shaft 16. Secured rigidly upon this rocking shaft is a 80 cam 17 which engages a plate 18, this plate being connected with a collar 19, on the rod 4.

At 20 is a tubular spindle which works 85 within the bearing 7, and fitted upon this tubular spindle is a gear wheel 21 for the purpose of turning it. A sleeve 22 is provided with an annular head 23 whereby it may be turned. The lower end of this sleeve 90 is threaded internally and fitted upon the upper end of the lower spindle 20 which is threaded for this purpose. The sleeve 22 is provided with a slot 24. A sleeve 25 extends into the upper end of the sleeve 22, fitting the same telescopically. A lug 26 is secured upon the sleeve 25 by screws 27, this lug 26, like the slot 24 in which it works, being inclined. The walls of the slot 24 surrounding the lug 26 are adapted to act somewhat after the manner of a cam, as herein-after described.

The sleeve 25 is provided with facets 27^a whereby it may be held by aid of a wrench, in fitting the parts together. This sleeve is 105 further provided at its upper end with a thread 28 and with slots 29. A collar 30, threaded internally, is fitted upon the

threaded end 28 and is provided with facets 31 whereby it may be turned, while the sleeve 25 is held stationary, as just stated, by the wrench.

- 5 The upper spindle is shown at 32 and is of considerably smaller diameter than the lower spindle 20. The upper spindle rests upon an annular shoulder 33 wherewith the sleeve 25 is provided. In order to couple the upper spindle 32 with the sleeve 25, it is let down into the same and lodged against the shoulder 33. The annular collar 30 is now turned so as to tighten the slotted portion of the sleeve 25 against the upper spindle.
- 10 This makes a water-tight joint.

A stout spring 24 engages the upper end of the lower spindle 20 and also engages the lower end of the sleeve 25. This spring is of such strength as to normally hold the various parts in the relation indicated in Fig. 3. Mounted upon the upper end of the upper spindle 32 is a ferrule 35 which carries brushes 36. At 37 is a bottle to be washed. The bottle 37 contains a thickened portion 38 due to a flaw in its make-up.

The operation of my device is as follows: Power being continuously applied to the lower spindle by aid of the gear 21, the lower spindle turns constantly and drives the upper spindle 32. The water, being forced upwardly through the lower spindle, finds its way out into the bottle 37 and flows downwardly, making its escape therefrom. The bottle 37, together with the plates 11, 12, 18, 35 has a vertical reciprocating motion well understood in this art and used for the purpose of bringing the brushes 36 into engagement with the entire interior of the bottle.

The tension of the spring 34 is such that normally this spring yields but little, if at all, during the washing of a bottle. Suppose, however, that the bottle contains an obstruction 38 and that this obstruction is engaged by the brushes 36. Naturally this develops a little pressure upon the upper end of the upper spindle 32, tending to force this spindle downwardly, thereby compressing the spring 34. Since this spring is tolerably strong the pressure due to the obstruction alone might, within itself, be insufficient to cause the upper spindle to descend. The slot 24 being inclined, however, and acting as a cam, the rotation of the sleeve 22 (under the constant application of power through the gear 21) causes the lug 26 to be drawn downwardly and in doing this the upper spindle 32 is moved slightly downward so that the brushes are disengaged from the obstruction. It will be noted in this connection that a portion of the power used for retracting the brushes when they encounter an obstacle, is supplied from the primary source of power used for actuating the various movable parts and is not supplied altogether by the pressure of the ob-

struction alone. It will also be noted that downward movement of the upper spindle and the consequent withdrawal of the brushes from the obstruction 38, are due, in a measure, to a differential movement taking place between the upper and lower spindles.

While for convenience I show the spring 34, lug 26 and parts immediately associated therewith, as located substantially at the junction between the upper spindle and the lower spindle, I do not limit myself thereby, for the reason that the said parts may be located at any convenient point intermediate the brush and the lower end of the revoluble stem which, in this particular instance, happens to be made up of the lower and upper spindles.

Having thus described my invention, I claim as new and desire to secure by Letters Patent:

1. The combination of a stem compressible in the general direction of its length, a brush mounted upon said stem, means for causing said stem to rotate, and mechanism controllable partly by an obstruction in the path of said brush and partly by the rotation of said stem, for compressing said stem in the general direction of its length.

2. The combination of a revoluble stem comprising two parts fitted telescopically together and movable relatively to each other, a spring for maintaining said parts in a predetermined normal position, a brush mounted upon one of said parts and adapted to encounter an obstruction occasionally, and means controllable partly by said obstruction and partly by the rotation of said stem, for compressing said spring and moving one of said parts of said stem relatively to the other part thereof.

3. The combination of a lower spindle of tubular form, an upper spindle of tubular form, a sleeve mounted upon said lower spindle and encircling a portion of said upper spindle, thereby forming a telescopic connection between said lower spindle and said upper spindle, a spring disposed intermediate said upper spindle and said lower spindle for the purpose of normally maintaining said spindles in a predetermined working relation, means for turning said lower spindle, mechanism connecting said sleeve with said upper spindle for the purpose of transmitting motion to said upper spindle, said mechanism being controllable partly by pressure upon said upper spindle and partly by the rotation of said lower spindle, for forcing said upper spindle downward, and a brush mounted upon said upper spindle.

4. The combination of a lower spindle, means for turning the same, a sleeve mounted upon said lower spindle and provided with a spirally disposed slot, an upper spindle, a sleeve mounted upon the lower

end thereof and telescoping with said sleeve upon said lower spindle, a lug mounted upon said sleeve connected with said upper spindle, said lug extending into said slot, a
5 brush mounted upon said upper spindle, and means for yieldingly holding said upper spindle relatively to said lower spindle.

In testimony whereof I have signed my name to this specification in the presence of two subscribing witnesses.

CHARLES K. VOLCKENING.
